SINGLE-SHEET SEPARATING AND FEEDING MECHANISM.

1,152,358.

Specification of Letters Patent. Patented Aug. 31, 1915.

Application filed May 6, 1915. Serial No. 26,232.

To all whom it may concern:

Be it known that we, JAMES D. REIFSNYDER and WALTER A. SAATMAN, citizens of the United States, residing at Philadelphia, in 5 the county of Philadelphia and State of Pennsylvania, have invented new and useful Improvements in Single-Sheet Separating and Feeding Mechanism, of which the following is a specification.

10 This invention relates to feeding mechanism such as used for feeding a machine of any kind which operates upon a blank sheet; for example, such machines as printing presses or gluing machines.

15 A principal object of the invention is to produce a simple mechanism which will operate to enable sheets to be taken one at a time from a pack, and operating so as to insure that not more than one sheet will be 20 fed at a time.

A further object of the invention is to provide improved means for crowding a pack of sheets toward a separating device or segregating device, operating so that the 25 pack advances automatically toward the separating device to compensate for the sheets that have been removed.

A further object of the invention is to provide a feeding mechanism by which the 30 foremost sheet of the pack is presented to the separating device in such a way as to coöperate with the separating device to facilitate the segregation or separation of the forward sheet from the pack and operating 35 so that the remaining sheets of the pack tend to withdraw or recede from the position of the foremost sheet and thereby overcome any tendency of the sheet or sheets nearest the foremost sheet from being separated from the pack simultaneously with 40 the foremost sheet.

A further object of the invention is to provide an oscillating device for oscillating the pack of sheets to facilitate the separation 45 of the foremost sheet of the pack and to provide automatic means for periodically advancing the oscillating device toward the pack, controlled by the condition of the pack, to insure that the pack will be held 50 intact and properly pressed or crowded toward the separating device.

A further object of the invention is to provide for adjusting the feeding mecha-

nism so as to properly present the foremost sheet of the pack and to maintain constantly 55 a driving connection to the feeding mechanism in any of the adjusted positions thereof.

Further objects of the invention will appear hereinafter.

The invention consists in the general combination of parts and simplicity of details to be described hereinafter, all of which contribute to produce an efficient feeding 60 mechanism.

The preferred embodiment of the invention is described in the following specification, while the broad scope of the invention is pointed out in the appended claims.

In the drawing, Figure 1 is a vertical section partly broken away, illustrating one embodiment of the invention and representing the same as applied to a gluing machine. This view shows the normal condition or phase of operation of the mechanism. Fig. 70 75 2 is a fragmentary view similar to Fig. 1 showing certain parts broken away and illustrating the mechanism in another phase of its operation. Fig. 3 is a plan representing the feeding mechanism as removed from the gluing machine; certain parts are shown in cross-section or broken away to further illustrate the mechanism shown in Fig. 1. Fig. 4 is an elevation representing the mechanism as viewed from the outer side. Fig. 85 5 is a vertical section, illustrating a pneumatic separating or segregating device and showing how the feeding mechanism may coöperate with such a mechanism.

Referring more particularly to the parts, 90 10 represents a feeding mechanism which, by way of illustration, is represented as working in conjunction with a gluing machine 11. The gluing machine illustrated 95 comprises a tank or reservoir 12 for the glue in which dips a wallower or glue roller 13 which conveys the glue to a distributer roller 14. On this distributer roller a plurality of glue applying rollers 15 roll, and one of these rollers such as the roller 15^a is 100 located at an exposed point so that it may lie adjacent to the upper end of a pack 16 of sheets 17 which are to be fed to the gluing machine. In the operation of the gluing machine, the peripheral surfaces of the roller 105 15^a become smeared with glue, and this

roller 15^a performs the function of a separating device or segregating device for taking the foremost sheet 18 from the pack whenever the pack is oscillated over against this roller. In order to accomplish this, the pack 16 is preferably supported so that the sheets are held or gripped at one edge such as their lower edges 19, so that the weight of the pack is not exerted on the foremost sheet, and the pack is permitted to be freely movable at its upper end so that it may be bodily raised or oscillated at the proper times over against the separating device such as the roller 15^a. The pack 16 is preferably supported on an inclined table 20 arranged so that it inclines upwardly toward the feeding point, that is, toward the separating device. From this arrangement, when the pack is oscillated forwardly to effect the separation of the foremost sheet, the remainder of the sheets in the pack tend to recede or gravitate back from the foremost sheet, and do not exert any pressure upon it while it is being removed.

25 In order to crowd or push the sheets in the pack 16 toward the separating device 15^a, there is provided a pusher or follower 21 at the back or lower side of the pack, which preferably comprises a movable member or base 22 supported at the table, and an oscillating plate 23 which is preferably pivotally mounted on the base at the point 24. There is also provided a mechanism such as the mechanism illustrated at 30 35, the function of which is to constantly oscillate the plate 23, and this mechanism is controlled automatically by the condition of the sheets in the pack, in such a way that when the pack is not sufficiently crowded, 40 the mechanism will operate to move the pusher bodily toward the pack. In this way the pusher automatically compensates for the removal of the sheets and keeps all the sheets remaining in the pack properly 45 pressed toward the feeding point. This mechanism is preferably actuated in a very simple manner through the medium of a reciprocating bar or rack 26 which preferably extends longitudinally of the table 50 and which is constantly reciprocated when the machine is in operation. The mechanism 25 has substantially two phases in this operation, in one of which the base 22 remains stationary while the oscillating plate 55 23 is continuously oscillated or swung on its pivot 24. In the other phase the oscillator is shifted or moved bodily toward the separator. The mechanism 25 also preferably includes a gear wheel 27 which meshes with 60 the teeth of the aforesaid rack 26 and this gear wheel is pivotally supported at 28 on the aforesaid base 22.

In order to accomplish the constant oscillation of the pusher plate 23, there is preferably provided a pawl 29 which is pivot-

ally attached to a pawl carrier 30 and said pawl carrier is connected by a link 31 with the plate. The faces of the nose 29^a of the pawl 29 are so inclined that it tends to throw itself out of engagement with the teeth of the wheel 27, but in the normal operation of the mechanism, the pawl is held from disengaging itself by means of a small latch 32 which is pivotally mounted at 33 on the base and pressed toward the pawl by a spring 34. 75 If there are sufficient sheets in the pack 16, the forward rocking movement of the plate will not be sufficient to permit the rear side of the pawl 29 to become disengaged from the latch 32, and hence the plate 23 will continue to oscillate without change. However, when a sufficient number of sheets have been removed, the pawl 29 will move far enough forward to pass out of engagement with the latch and disconnect itself from the gear 85 wheel, assuming a position such as that illustrated in Fig. 2. Then, on account of the pressure of the pack 16 and the weight of the plate 23, the pawl carrier and pawl will swing toward the left. In doing this, 90 the end of the pawl strikes a shoulder 35 on the latch 32 and swings the latch outwardly so as to let the pawl pass the shoulder, whereupon the spring 34 brings back the latch to its normal position in which it 95 locks the pawl. In this way, the pawl shifts itself automatically backward to take a new hold on the teeth of the gear wheel. In other words, this mechanism operates in such a way that the position of the pawl is 100 automatically shifted back on the gear wheel if the sheets in the pack permit excessive movement of the pusher plate. In addition to this, the mechanism operates simultaneously to effect the automatic advance of the base inwardly, if the plate should have an excessive movement such as that referred to. To effect this result, there is preferably provided a detent pawl 36 which affords means for holding the gear wheel 27 against a return movement in case it has an excessive movement in its forward rocking or rotation. That is, if the sheets in the pack permit the plate 23 to swing sufficiently far in a forward direction, the tooth 27^a of the gear wheel 27, which is in engagement with the inclined face 37 of the detent pawl 36, will push the pawl back against the resistance of its spring 38 and this tooth will then pass above the pawl so that the pawl 110 will engage the under side of the tooth and prevent the gear wheel from rotating back. On account of the fact that the gear wheel rests on the rack, this holding of the gear wheel against a return movement gives the gear wheel a relative rotation along the rack so that the gear wheel creeps along the rack whenever this shifting of the pusher occurs. In order to prevent any tendency of the base 115 120 125 130 22 to move back when advanced in this way,

there is preferably provided a ratchet rack 39 having inclined teeth with which cooperates a detent pawl 40 carried in the base and pressed toward the ratchet rack 5 by a suitable spring 41.

In order to hold up the pusher plate 23 in the absence of a pack 16 on the table, there is preferably provided an adjustable stop on the base which may be in the form 10 of a set screw 42 adapted to engage a lug 43 which projects from the pawl carrier or arm 30.

In the operation of this mechanism, it is understood that normally the forward motion 15 of the gear wheel is not sufficient to cause a complete depression of the detent pawl 36, the normal operation consisting simply in that the tooth 27 which is in engagement with this pawl partially depresses it but withdraws before the tooth has moved far enough to pass the point of the pawl. If the forward swinging movement of the plate 23 permitted by the pack is sufficient, however, the tooth of the gear wheel will be 20 caught and the wheel will not return in the backward movement of the rack but is locked against rotation by the pawl so that as the rack moves inwardly it pulls the base 22 up along the ratchet rack 39. At each forward 25 movement of the pusher plate 23, the upper portion of the pack is oscillated over against the separating device 15^a and as the pusher plate 23 recedes, there is a recession by gravity of all the sheets in the pack except 30 the foremost sheet which adheres to the separating device.

The rack 26 is preferably guided on the table by means of pin and slot connections 44. The rack may be reciprocated in any 40 suitable manner. In the present instance, it is illustrated as reciprocated in one direction by means of a spring 45, one end of which is anchored at 46 on the lug 47 of the table, and the other end is attached to a 45 pin 48 (see Fig. 3). This pin 48 is preferably carried on a rock lever 49 which is rocked automatically by the machine and preferably through the medium of a cam 50. Every time the cam 50 comes around, 50 it engages the roller 51 at the end of the lever (see Fig. 4) and this rocks the lever so as to pull the rack inwardly on the table. The spring 45 returns the rack and the lever to their normal position after the cam has 55 passed.

Means are preferably provided for effecting a substantially vertical adjustment of the feed table 20. This is preferably accomplished by means of an adjusting screw 60 52 (see Fig. 1), the lower portion of which is swiveled in a bearing 53 so that the screw passes through a threaded sleeve or nut 54 attached to the table. By rotating the screw 52, evidently the table can be raised, as the 65 table is guided in this vertical movement on

a suitable guide 55 (see Fig. 3). The direction of movement of the table in adjusting it in this manner is parallel with a shaft 56 which carries the aforesaid cam 50. The cam 50 is provided with a feather or spline 70 running in a longitudinal groove 57 in the shaft so that the cam can slide along the shaft to any point but will be constantly rotated by the shaft. In order to slide the cam with the table when the table is moved up 75 or down, the cam is preferably provided with a grooved collar 58, the groove of which is engaged by a plate 59 attached to an arm 60 extending laterally from the table (see Fig. 4). If desired, this plate 59 may 80 be connected by a loose pivot 61 with the arm 60 so as to allow a slight movement at this point to compensate for any slight inaccuracy in alignment of the cam shaft 56. The cam shaft 56 is preferably continuously 85 driven by means of bevel gears 62 from a shaft 63.

The feeding mechanism may be used with any kind of separating device other than that illustrated in Fig. 1; for example, it 90 may be used with a pneumatic separating device. For some reasons it is particularly useful in this particular connection; for example, on account of the fact that in pneumatic devices there is a tendency for the sheet in a pack adjacent to the foremost sheet to be drawn by the suction over against the foremost sheet and move away from the pack with it when the foremost sheet is separated. With this mechanism the tendency of the pack to recede from the foremost sheet, however, operates to prevent any such faulty operation. Such a pneumatic separating or segregating device is illustrated in Fig. 5. In this view, 64 represents a pneumatic roller or picker roller having a perforation or perforations 65 through its wall, the interior or chamber 66 within the roller being connected by a suitable hose 67 with a vacuum device which periodically produces a partial vacuum in the roller. When the pack has been oscillated over so as to bring the foremost sheet of the pack against the picker roller, the perforation 65 is on the side of the roller toward the pack and comes in contact with the edge of the foremost sheet. The operation of the vacuum device is timed so that at this moment a partial vacuum exists in the roller and the suction causes the edge of the sheet to adhere to the roller; and this causes the roller to take the sheet from the pack. After the perforation 65 has passed the presser roller 68 over the pneumatic roller, the vacuum is released and the rotation of the two rollers 64 and 68 then advances the sheet down a feed plate 69 from which the sheet may pass on into any suitable mechanism such as printing press mechanism 70.

In order to guide the pack of sheets on 130

one side, there is preferably provided a guide rod or bar 71 the outer end of which is supported in a bracket 72 which is adjustably clamped in a slot 73 in the table.

5 A horizontal slot 74 through the pusher plate receives this bar and prevents it from interfering with the operation of the pusher plate.

It is understood that the embodiment of 10 the invention set forth herein is only one of the many embodiments or forms the invention may take, and we do not wish to be limited in the practice of the invention nor in our claims to the particular embodiment 15 set forth. Furthermore, we may use any feature of our invention without the other features.

What we claim is:

1. In a feeding mechanism, in combination, means for supporting a pack of sheets 20 with the adjacent edges on one side of the pack freely movable and without the weight of the pack being exerted on the foremost sheet, a movable member movable on said 25 supporting means, and means movably mounted thereupon for periodically moving the sheets in the pack at said adjacent edges toward the feeding point to present the foremost sheet and to coöperate in effecting 30 the segregation of the foremost sheet, said last named means operating to permit a recession of the remainder of the pack when the foremost sheet is being segregated.

2. In a feeding mechanism, in combination, means for supporting a pack of sheets 35 at an edge of the sheets, said means permitting a free movement of the sheets at the opposite edge, a movable member movable on said supporting means, and means mov- 40 ably mounted thereupon for periodically moving the free edges of the sheets of the pack forwardly to present the foremost sheet to a segregating device, said last named means permitting the recession of the 45 remainder of the pack when the foremost sheet is being segregated, said movable member operating to clamp the sheets adjacent said supporting means.

3. In a feeding mechanism, in combination, an inclined support for supporting a 50 pack of sheets on edge, means engaging the pack on the lower side thereof for periodically moving the pack to present the upper sheet in the pack to a segregating device, 55 said inclined support inclined upwardly toward the position of the segregating device whereby the pack of sheets will gravitate away from the foremost sheet when the same is taken by the segregating device.

60 4. In a feeding mechanism, in combination, means for supporting and clamping a pack of sheets at an edge thereof, means for oscillating the free edges of the sheets of the pack toward a segregating device, said sup- 65 porting means inclining upwardly toward

the position of the segregating device whereby the pack of sheets will gravitate away from the foremost sheet when the same is presented to the segregating device.

5. In a feeding mechanism, in combination, means for supporting a pack of sheets at an edge of the sheets, a segregating device, said supporting means permitting a free movement of the sheets at their unsupported edges toward said segregating device, means for raising the free edges of the sheets of the pack to present the foremost sheet to said segregating device, said last named means being located lower than the pack to permit the recession by gravity of the remainder of the pack from the foremost sheet when it is being segregated. 70

6. In a feeding mechanism, in combination, a segregating device, means for supporting the pack of sheets at an edge of the sheets and so that the pack tends to gravitate at the free edges of said sheets away from said segregating device, and means for raising the free edges of the sheets of the pack to present the foremost sheet to said segregating device, said last named means permitting the recession by gravity of the remainder of the pack from the foremost sheet when being segregated. 75

7. In a feeding mechanism, in combination, an inclined support for a pack of sheets, a pusher for engaging the back of the pack to force the same upon the inclined support, means for oscillating said pusher to move the front of the pack toward the feeding point to present the foremost sheet of the pack to the segregating device and to permit the pack to gravitate away from the foremost sheet in effecting the segregation of the foremost sheet of the pack, and automatic means for periodically moving the said pusher bodily toward the feeding point. 95

8. In a feeding mechanism, in combination, means for supporting a pack of sheets, a pusher for engaging the back of the pack, 100 including a base and an oscillator plate pivotally supported on the base, means for oscillating said pusher to move in the front of the pack toward the feeding point to co-operate in effecting the segregation of the foremost sheet of the pack, and automatic means for periodically moving the said base toward the feeding point. 105

9. In a feeding mechanism, in combination, an inclined feed table for supporting 110 the lower edges of a plurality of sheets arranged in a pack with the sheets standing in a more or less upright position, a pusher for engaging the lower side of the pack, means for oscillating said pusher to move the upper portion of the pack in one direction of movement of the pusher to bring the foremost sheet into position to be taken from the pack, and to permit the pack to gravitate away from the foremost sheet when the 115 120 125 130

same is being taken from the pack, and automatic means for periodically moving said pusher bodily toward the feeding point.

10. In a feeding mechanism, in combination, a feed table for supporting the lower edges of a plurality of sheets arranged in a pack with the sheets standing in a more or less upright position, a pusher for engaging the back of the pack, means for oscillating said pusher to move the upper portion of the pack and bring the foremost sheet into position to be taken from the pack, and automatic means for periodically moving said pusher bodily toward the feeding point, controlled by the relation of the pusher.

11. In a feeding mechanism, in combination, a pusher for crowding a pack of sheets toward a segregating device comprising an oscillating member, means for oscillating said oscillating member to swing an edge of the pack toward the segregating device and to coöperate with the segregating device to effect the segregation of the foremost sheet of the pack, and means controlled by an excessive oscillating movement of said oscillating member for automatically moving said pusher bodily inwardly to crowd the pack.

12. In a feeding mechanism, in combination, a pusher for crowding a pack of sheets toward a segregating device comprising an oscillating member, means for oscillating said oscillating member to swing an edge of the pack toward the segregating device and to coöperate with the segregating device to effect the segregation of the foremost sheet of the pack, means controlled by an excessive oscillating movement of said oscillating member for automatically moving said pusher bodily inwardly to crowd the pack, and means for checking said pusher against moving bodily rearwardly.

13. In a feeding mechanism, in combination, a pusher for crowding a pack of sheets in an upward direction toward a segregating device, comprising an oscillating member, means for oscillating said oscillating member to swing a portion of the pack toward the segregating device and to coöperate with the segregating device to effect the segregation of the foremost sheet of the pack, and means controlled by an excessive oscillating movement of said oscillating member for automatically moving said pusher bodily inwardly to crowd the pack, a detent rack, and a pawl coöperating therewith to prevent a backward bodily movement of said pusher.

14. In a feeding mechanism, in combination, a feed table, a pusher movable along said table for crowding a pack of sheets toward a segregating device, said pusher comprising a base supported at the table, and a pusher plate supported on said base, means for moving said pusher plate to swing a

part of the pack toward the segregating device to coöperate with the segregating device to effect the segregation of the foremost sheet of the pack, and means controlled by the amount of movement of said pusher plate permitted by the pack for automatically moving said base toward the pack.

15. In a feeding mechanism, in combination, a feed table, a pusher movable along said table for crowding a pack of sheets toward a segregating device, said pusher comprising a base supported at the table, and a pusher plate supported on said base, means for moving said pusher plate to swing a part of the pack toward the segregating device to coöperate with the segregating device to effect the segregation of the foremost sheet of the pack, said means including a wheel, a pawl engaging with said wheel and connected with said pusher plate, and means for rocking said wheel.

16. In a feeding mechanism, in combination, a feed table, a pusher movable along said table for crowding a pack of sheets toward a segregating device, said pusher comprising a base supported at the table, and a pusher plate supported on said base, means for moving said pusher plate to swing a part of the pack toward the segregating device to coöperate with the segregating device to effect the segregation of the foremost sheet of the pack, said means including a gear wheel, a pawl engaging with said wheel and connected with said pusher plate, and a reciprocating rack meshing with said gear wheel for rocking the same and for pulling said base toward said pack.

17. In a feeding mechanism, in combination, a feed table, a pusher movable along said table for crowding a pack of sheets toward a segregating device, said pusher comprising a base supported at the table and a pusher plate supported on said base, a bar movable longitudinally of said table, and mechanism actuated by said bar for oscillating said pusher plate and for periodically moving said base toward the pack.

18. In a feeding mechanism, in combination, a feed table, a pusher movable along said table for crowding a pack of sheets toward a segregating device, said pusher comprising a base supported at the table and a pusher plate supported on said base, a bar mounted to reciprocate longitudinally of said table, a gear wheel rotatably mounted on said base, rocked by said bar and movable along said bar when said base moves toward the pack, and a connection from said gear wheel to said pusher plate for rocking said pusher plate constructed to disconnect automatically when said pusher plate has an excessive oscillating movement.

19. In a feeding mechanism, in combination, a feed table, a pusher movable along said table for crowding a pack of sheets to

ward a segregating device, said pusher comprising a base supported at the table and a pusher plate supported on said base, a bar mounted to reciprocate longitudinally of 5 said table, a gear wheel rotatably mounted on said base rocked by said bar and movable along said bar when said base moves toward the pack, a connection from said gear wheel to said pusher plate for rocking 10 said pusher plate constructed to disconnect automatically when said pusher plate has an excessive oscillating movement, and means for periodically checking the rocking movement of said wheel in one direction to effect 15 an inward movement of said base toward the pack.

20. In a feeding mechanism, in combination, a feed table, a pusher movable along said table for crowding a pack of sheets toward a segregating device, said pusher comprising a base supported at the table and a pusher plate supported on said base, a gear wheel rotatably mounted on said base, a reciprocating rack extending longitudinally 25 of said table and meshing with said gear wheel to rock the same to and fro, a connection from said pusher plate to said gear wheel for oscillating the pack and constructed so that the pack limits the movement 30 of the pusher plate and also limits the rocking movement of said gear wheel in the forward direction, means on said base for checking the gear wheel against a backward movement after an excessive rocking movement 35 in the forward direction and thereby causing said gear wheel to roll on said rack toward the pack to advance the pusher base toward the pack.

21. In a feeding mechanism, in combination, a feed table, a pusher movable along said table for crowding a pack of sheets toward a segregating device, said pusher comprising a base supported at the table and a pusher plate supported on said base, a gear 40 wheel rotatably mounted on said base, a reciprocating rack extending longitudinally of said table and meshing with said gear wheel to rock the same to and fro, a connection from said pusher plate to said gear 45 wheel for oscillating the pack and constructed so that the pack limits the movement of the pusher plate and also limits the rocking movement of said gear wheel in the forward direction, means on said base 50 for checking the gear wheel against a backward movement after an excessive rocking movement in the forward direction and thereby causing said gear wheel to roll on said rack toward the pack to advance the pusher base 55 toward the pack, and means for preventing a backward movement of said base on said table.

22. In a feeding mechanism, in combination, a feed table, a pusher movable along 60 said table for crowding a pack of sheets to-

ward a segregating device, said pusher comprising a base supported at the table and a pusher plate supported on said base, said table being inclined so that the pack tends to fall back upon said pusher plate, a gear 70 wheel mounted on said base, means for actuating said pusher plate by said gear wheel including a pawl engaging said gear wheel, said pawl operating to become disengaged from said gear wheel upon an excessive forward oscillating movement of said pusher plate and permitting the pressure of the pack on said pusher plate to move said pawl back along the gear wheel to reengage the same.

23. In a feeding mechanism, in combination, a feed table, a pusher movable along said table for crowding a pack of sheets toward a segregating device, said pusher comprising a base supported at the table and a pusher plate supported on said base, said table being inclined so that the pack tends to fall back upon said pusher plate, a gear 80 wheel mounted on said base, means for actuating said pusher plate by said gear wheel including a pawl engaging said gear wheel, 85 a latch co-operating with said pawl for normally holding said pawl in engagement with said gear wheel and permitting the disengagement of said pawl from said gear wheel upon an excessive forward movement of said pusher plate, the weight of the pack and said pusher plate operating to move said pusher back and move said pawl back to engage the gear wheel at another point, 90 said latch operating to effect the reengagement of said pawl with said gear wheel.

24. In a feeding mechanism, in combination, a feed table, a pusher movable along said table for crowding a pack of sheets toward a segregating device, said pusher comprising a base supported at the table and a pusher plate supported on said base, a reciprocating rack movable longitudinally of said table, a gear wheel pivotally supported on 100 said base and meshing with said rack, a pawl carried thereby engaging said gear wheel, said pawl carrier connected with said pusher plate to enable said gear wheel to impart a rocking movement to said pusher plate, and a detent pawl engaging said gear wheel and operating to prevent an unlimited backward rotation of said gear wheel and thereby causing said gear wheel to move 110 upwardly on said rack and advance said pusher base toward the pack.

25. In a feeding mechanism, in combination, a feed table, a pusher movable along said table for crowding a pack of sheets toward a segregating device, said pusher comprising a base supported at the table and a pusher plate supported on said base, a reciprocating rack movable longitudinally of 120 said table, a gear wheel pivotally supported on said base and meshing with said rack, a 125

- pawl carried thereby engaging said gear wheel, said pawl carrier connected with said pusher plate to enable said gear wheel to impart a rocking movement to said pusher plate, a detent pawl engaging said gear wheel and operating to prevent an unlimited backward rotation of said gear wheel and thereby causing said gear wheel to move upwardly on said rack and advance said pusher base toward the pack, and a spring pressed latch coöperating with said first named pawl for normally holding the same in engagement with said gear wheel and permitting the disengagement of said pawl upon an excessive forward rocking movement of said pusher plate, said pusher plate operating to move back automatically and effect the reengagement of said pawl in cooperation with said latch at another point on said gear wheel.
26. In a feeding mechanism, in combination, a feed table for supporting a pack of sheets, a pusher movable along said table for crowding the pack of sheets toward a segregating device, mechanism for oscillating said pusher, and for automatically moving said pusher bodily toward the pack periodically, manually operated means for adjusting the height of said table, and means for maintaining a driving connection to said mechanism at the different adjusted positions of said table.
27. In a feeding mechanism, in combination, a feed table for supporting a pack of sheets, a pusher movable along said table for crowding the pack of sheets toward a segregating device, mechanism for oscillating said pusher, and for automatically moving said pusher bodily toward the pack periodically, manually operated means for adjusting the height of said table, a shaft extending substantially parallel to the direc-
- tion of said adjustment of said table, and means mounted to slide on said shaft for driving said mechanism in any adjusted position said table may assume.
28. In a sheet separating and feeding mechanism, in combination, means for supporting a pack of sheets on edge, and means for oscillating the pack to bring a portion of the face of the foremost sheet of the pack into contact with a separating device to withdraw a sheet at each successive oscillation of the pack.
29. In a sheet separating and feeding mechanism, in combination, means for supporting a pack of sheets on edge, a member behind the pack, and means for rocking said member to oscillate the pack bodily to bring a portion of the face of the foremost sheet of the pack into contact with a separating device to withdraw a sheet at each successive oscillation of the pack.
30. In a sheet separating and feeding mechanism, in combination, means for supporting a pack of sheets on edge, a member behind the pack, means for rocking said member to oscillate the pack bodily to bring a portion of the face of the foremost sheet of the pack into contact with a separating device to withdraw a sheet at each successive oscillation of the pack, and means for moving said rocking member bodily toward the separating device to compensate for the sheets removed at the forward side of the pack.
- In testimony whereof we have hereunto set our hands in presence of two subscribing witnesses.
